ELECTRIC FLASHING DEVICE.

Application filed February 6, 1924. Serial No. 690,970.

This invention relates to improvements in electric flashing devices wherein a light is automatically caused to glow at uniformly intermittent intervals.

5 One of the objects of the invention is to provide automatic means actuated by an electric current for producing such results in a reliable, positive and practical manner.

Another purpose is to produce a flashing 10 device in which the periodicity of light emanations can be effectively controlled.

A further aim is in the provision of an extremely durable device, practically frictionless, unusual in the simplicity, and, due 15 to the substantially indestructible nature of the contact making element, may be depended upon to operate at a predetermined rate of speed continuously for a long period of time without personal attention.

20 These and other important aims, objects and purposes, which will later appear, are accomplished by the novel construction, combination and arrangement of parts herein-after described and shown in the accompanying drawing, forming a material part of this disclosure, and in which:—

Figure 1 is a front elevational view of the operative mechanism, in an embodiment of the invention, the same being shown in a 30 normal position, the electric circuit being closed.

Figure 2 is a similar view of the same but showing the position of parts when the circuit is open.

35 Figure 3 is a side view of Figure 2.

Figure 4 is an enlarged plan view of the contact making and breaking device in detail, parts being broken away to disclose the construction.

40 Referring more in detail to the drawing, the numeral 10 designates the support or base plate to which the mechanism is attached, this plate being of non-conducting or dielectric material and of such shape and 45 dimension as may be desirable.

An electrical current, from any convenient source is indicated as being conducted to the plate by the wires 11 and 12 connected to the binding posts 13 and 14, the latter having a connection 15 with a lamp, diagrammatically shown and designated by the 50 numeral 16 and having another connection 17 leading to the binding post 18.

Also leading from the binding posts 14 and 18 are coiled flexible connections re-

spectively 19 and 21 in circuit with an electro-magnet 20 having magnetizable heads or end plates 22 and 23 held by an axial bolt 24, the lower head 23 having a flanged base 25 containing an arcuate slot 26, permitting 60 adjustment on the clamp screw 27 by which it is held to the plate 10, the magnet being connected in parallel with the lamp 16.

The upper head 22 is provided with a similar but narrower base member 28 of 65 considerable length, its upper end being pivoted to the upper central portion of the plate 10 by the screw 29.

A third conductor 30 leads from the binding post 18 to another binding post 31 on 70 the plate 10, which can be placed in circuit with the binding post 13 in the manner further described.

At one side of the pivoted magnet base 28, a pair of posts 32 are fixedly set in the 75 plate 10 and rigidly carried by them are a pair of support plates 33 arranged in spaced parallel relation to each other and from the base plate 10.

Pivoted between the plates 33, on the pin 80 34 is a flat pendulum 35 adapted to be attracted, in the manner of an armature, by the magnet 20 when the latter is energized, and fixed on the upper end of the pendulum 35 is a curved strip 36 having inturned terminals 37, resembling in general appearance the escapement click of a pendulum controlled clock.

Another pin 38, carried between the support plates 33, near their upper ends, acts 90 as a pivot for an oscillatable bar 40 made of non-conducting material, its ends extending uniformly outward from its pivoted point and its lower surface normally clearing the ends 37 of the curved strip 36. 95

Mounted on the upper surface of the bar 40, near its ends, are opposed snap sockets 41 and 42 respectively, in electrical engagement with the binding posts 13 and 31 by coiled flexible connections 43 and 44 arranged to permit the bar 40 to tilt without interference.

A tube 45, preferably of glass, is provided with sealed end caps 46 and 47, through which extend conductors 48 and 49, the former of which has its inner end 51 positioned substantially central of the tube 45.

The other conductor 49 has its inner end 53 disposed substantially in a plane trans-

verse to the inner edge of the cap 47 and spaced a considerable distance from the corresponding terminal 53, both of which are axially disposed within the tube 45 and normally, when the tube is horizontal, are in electrical contact with a body of mercury 54 which fills approximately one-fourth of the space in the tube and is free to flow therein, when the tube is in an inclined position, to completely clear the terminal 53 and thus break the circuit.

In operation, the parts being disposed as shown in Figure 1, current entering by the wire 11 to the binding post 13, is conducted by the coil 43 to the clip 41 in electrical contact with the cap 46 to the conductor 48 and its terminal 51.

The mercury 54 conveys the current to the terminal 53 and conductor 49 to the cap 47, in electrical contact with the clip 42 and thence by the wire 44 to binding post 31, from which current is conveyed by the wire 30 to the binding post 18.

From the post 18 current is conducted by the wire 17 to energize the lamp 16, thence by wire 15 to post 14 and returned to its source by wire 12.

Current is also conducted from the post 16 by conductor 21, to energize the magnet 20 and returned by wire 19 to post 14 engaging the return wire 12.

Thus when the lamp 16 glows the magnet 20 will be energized, causing it to attract the pendulum armature 35 bringing the end 25 of the strip 36, adjacent the magnet, to strike the bar 46 causing it to tilt on the pivot 38 (see Figure 2) and the mercury 54 to flow into the lower end of the tube, breaking the circuit between the terminals 51 and 53, thus cutting off current to the lamp and magnet simultaneously.

Thereupon the weight of the armature 35 moves it by gravity into the position shown in Figure 1 and the sequence of operation 45 is again renewed.

Means for increasing or decreasing the speed or time limit of operation are provided for by either changing the resistance of the electro-magnet 20 by adjusting the magnet on the pivot 29 towards or away from the armature so as to strengthen or weaken its pull.

The strength of the magnet may also be changed by the interposition of a resistance in the circuit or by moving its iron core relative to the magnet coil, or by substituting a coil of different resistance.

Obviously changing the weight of the pendulum armature, or the distance between its pivotal point and the electro-magnet would have the effect of controlling the rate of operation.

It is to be noted that the absence of springs, durability of circuit making medium, freedom from friction and simplicity

of parts, offer special advantages in producing an intermittently lighted signal of absolute reliability.

Although the foregoing is descriptive of the preferred embodiment of the invention, it will be apparent that minor changes may be made in its construction, without the exercise of invention or conflicting with the scope of the claims hereto appended.

Having thus described our invention, what we claim as new and desire to secure by Letters Patent, is:—

1. In an automatic circuit breaker, the combination of an electro-magnet, a pendant bar armature pivoted to swing towards the side of said magnet by attraction and away by gravity, means actuated by said armature for intermittently opening and closing the circuit, and means for adjusting said magnet with respect to the armature. 80

2. In an automatic circuit breaker, the combination of an electro-magnet, an elongated base for said magnet, said base being pivoted at a point remote from the magnet, a pendulous bar armature for said magnet, said armature being oscillatably mounted, and a switch actuated by the swing of said armature. 90

3. In an automatic circuit breaker, the combination of a single electro-magnet, a pivoted support therefor, a pendulous bar armature for said magnet, said armature being oscillatably mounted, a switch actuated by the swing of said armature, and means for adjusting the distance between said magnet and the axis of the armature. 95

4. In an automatic circuit breaker, the combination of a vertical base plate, an electro-magnet pivoted near the upper edge of said plate, a pendulous lever bar armature for said magnet, said armature being pivotally suspended at a point below the pivot point of said magnet, a switch actuated by the swing of said armature, a weight carried on said armature, and means for adjusting said weight. 105

5. In an automatic circuit breaker, the combination of a fixed vertical base plate, an electro-magnet pivoted on the upper portion of said plate, an armature pivoted to said plate below the point of suspension of said magnet at one end to swing towards or from said magnet, a switch oscillatably mounted above said armature and below the point of suspension of said magnet, means on the armature to tilt said switch and means in said switch adapted to close the circuit when the switch is in one position, said means opening the circuit when the switch is in another position. 115

6. An automatic circuit breaker comprising in combination with a vertical support plate, of a lever bracket pivoted at one end and slotted arcuately at the other, means for adjustably securing said bracket to said 130

plate, an electro-magnet mounted in said bracket, said magnet being in the electric circuit, a pendulous armature pivoted on said plate, a plate pivoted in a plane parallel to and above the axis of said armature, means on said armature adapted to contact with said plate near the limits of its oscillatory movement, clips on the ends of said pivoted plate, a sealed mercury carrying tube removably

engaged in said clips, contacts in the ends 10 of said tube engaging the mercury when the tube is on one position, and electrical connections with said contacts, one of said connections leading to the magnet.

In testimony whereof we have signed our 15 names to this application.

ABRAHAM SPRUNG.

DAVID H. DARRIN.
